UNITED STATES PATENT OFFICE

HENRY E. LENNON AND ROBERT E. O'NEIL, OF MILFORD, NEW HAMPSHIRE

CONVERTIBLE STRUCTURE

Application filed November 27, 1929. Serial No. 410,120.

The chief object of this invention is to provide a structure suitable for use as a camping outfit, and adapted to constitute either a table, or a cabinet adapted to hold various articles used in camping.

Another object is to enable the structure, when used as a table, to be supported in a suitably elevated position.

Another object is to enable the structure to be used as a chair.

Of the accompanying drawings forming a part of this specification,

Figure 1 is a side view, showing a structure embodying the invention, conditioned for use as a table.

Figure 2 is an end view of the structure conditioned as shown by Figure 1.

Figure 3 is a side view of the structure conditioned for use as a chair.

Figure 4 is a perspective view, showing the structure partly closed for transportation.

Figure 5 is a perspective view on a smaller scale, showing the structure entirely closed.

Figure 6 is a view similar to Figure 4, omitting the drawer and the hinged sections of the table top, one of said hinged sections being shown by dotted lines.

Figure 7 is a perspective view, showing a different construction of the table top.

The same reference characters indicate the same parts in all of the figures.

Our improved convertible structure comprises a rigid body portion including a bottom member 12, spaced apart upright members 13, at opposite ends of the bottom member, and an inner member 14, located between the members 13, and constituting the top of a drawer guide and the bottom of a storage space above said guide, other portions of the drawer guide being provided by the members 12 and 13 as indicated by Figure 6.

15 designates a drawer movable in the guide.

45 A table top is supported by the members 13 above the drawer guide. Said top extends between the members 13, and is adapted to constitute the top or cover of the storage space.

50 In the embodiment of the invention shown

by Figures 1, 2, 3, 4, 5 and 6, the top includes two sections or leaves 16, connected by hinges 17 with heads 18 fixed to the members 13. Said sections are adapted to swing inward between said members, as shown by Figure 3, and cooperate therewith in forming arms of a chair, the seat of which is provided by the inner member 14. The sections 16 may be releasably supported horizontally by any suitable means, such as horizontal supporting arms 19, connected by hinges 20 with the members 13, and arranged to swing from said members, as shown by Figure 1, and by dotted lines in Figure 6, to horizontally support the sections 16, and against said members, as shown by Figure 3, and by full lines in Figure 6, to permit the sections 16 to swing downward. The heads 18 in this embodiment of the invention constitute fixed sections of the table top.

The structure comprises also side members 22, connected by hinges 23, with the bottom member 12, and adapted to close opposite sides of the storage space above the drawer, and prevent access to the latter, any suitable means being provided for releasably confining the side members 22 in their closing positions. In this instance, we embody said means in slots 24 in the swinging ends of the side members 22, and ears 25 fixed to one of the top sections 16, and arranged to enter the slots. Each ear 25 may be perforated to engage a padlock 26, as indicated by Figure 5.

When the side members are closed, as shown by Figure 5, the structure constitutes a cabinet enclosing the drawer 15, and a storage space above the drawer.

The side members 22 may be swung downward from the bottom member 12, as shown by Figures 1, 2 and 3, to constitute legs supporting the other portions of the structure suitably raised above a floor or other support, means such as a hooked rod 28 (Figure 2) being provided for the releasably confining the side members in their supporting position.

The table top preferably includes end sections 29, connected by hinges 30 with the upright members 13, and adapted to project

horizontally in opposite directions therefrom, to extend the table top as shown by Figure 1, means such as hinged arms 31 (Figure 6) being provided for releasably confining the sections 29 in their top-extending position, said arms being adapted to be displaced to permit the sections 29 to swing downward.

It will now be seen that the structure, whether used as a table, as shown by Figures 10 1 and 2, or a chair, as shown by Figure 3, may be supported in a suitably raised position.

The structure, as shown by Figure 7, differs from that shown by the preceding figures, in that the table top portion which covers the storage space above the drawer, and is designated by 33, is fixed to the upright members 13, so that the structure is not convertible into a chair. The structure may be 20 otherwise constructed as previously described.

The structure may be so proportioned that when it is closed as shown by Figure 5, it may be carried on the running board of an automobile.

25 We claim:

1. A convertible structure comprising a rigid body portion including a bottom member, spaced apart upright members at opposite ends of the bottom member, and an inner member located between the upright members and constituting the top of a drawer guide and the bottom of a storage space, other portions of the guide being provided by the bottom and upright members, a drawer movable in said guide, and a table top supported by the upright members above the drawer guide, said top extending between the upright members and constituting the cover of said storage space, and side members hinged 40 to the bottom member and adapted to close opposite sides of the storage space and prevent access to the drawer, means being provided for releasably confining the side members in their closing positions, the side members being adapted to extend downward from the bottom member and constitute legs supporting the body portion and top in a raised position, means being provided for releasably confining the side members in their supporting position.

2. A convertible structure comprising a rigid body portion including a bottom member, spaced apart upright members at opposite ends of the bottom member, and an inner member located between the upright members and constituting the top of a drawer guide and the bottom of a storage space, other portions of the guide being provided by the bottom and upright members, a drawer movable 55 in said guide, and a table top supported by the upright members above the drawer guide, said top extending between the upright members and constituting the cover of said storage space, and side members hinged to the bottom member and adapted to close oppo-

site sides of the storage space and prevent access to the drawer, means being provided for releasably confining the side members in their closing positions, the table top including sections hinged to the upright members and adapted to extend horizontally between said members to constitute a top, and to swing downward to cooperate with said members in forming arms of a chair, the seat of which is formed by the said inner member, means being provided for releasably supporting said sections horizontally.

In testimony whereof we have affixed our signatures.

HENRY E. LENNON.
ROBERT E. O'NEIL.
